(57) **CLAIM**

The ornamental design for a vehicle camera, as shown and described.

DESCRIPTION

FIG. 1 is a perspective view of our vehicle camera;

FIG. 2 is another perspective view thereof;

FIG. 3 is another perspective view thereof;

FIG. 4 is another perspective view thereof;

FIG. 5 is a front view thereof;

FIG. 6 is a back view thereof;

FIG. 7 is a right side view thereof;

FIG. 8 is a left side view thereof;

FIG. 9 is a top view thereof; and,

FIG. 10 is a bottom view thereof.

As illustrated in FIGS. 1-3 and 6-8, the sides of the vehicle camera can include parallel air vents. As illustrated in FIGS. 4, 1-4, 9, and 10, the top and the bottom of the vehicle camera can include attachment openings. As illustrated in FIGS. 4, 7, 8, and 10, a display portion can be movably connected to the body of the vehicle camera with a rotating element. The broken lines illustrate features of the vehicle camera that form no part of the claimed design.
